WEAVING MACHINE

Application filed September 20, 1926. Serial No. 136,518.

This invention relates to the art of weaving, and more particularly to improvements in machinery therefor.

It is an object of this invention to provide a new and improved shuttle transfer mechanism.

It is another object to provide a mechanism in which the shuttle is thrown through the air from one shuttle carrier to the other, but in which the shuttle is always supported.

It is a further object to provide a mechanism for holding the shuttle thread taut during the beating-up operation.

It is a still further object to provide a weaving machine which is capable of handling cord or stiff materials, such as fine wire, of any desired diameter, and particularly for weaving rubberized cord and heavy fabrics.

Previous attempts to weave rubberized cord have been unsuccessful, partially due to faulty machine design, and partially because the soft rubber adhered to the mechanism and prevented it from functioning properly.

Both of these difficulties have been overcome in the machine which forms the subject matter of the present invention, as will be apparent from what follows.

With the above and other objects in view, which will be apparent as the description proceeds, I have set forth my invention in the following specification, taken in connection with the accompanying drawings, in which:

Fig. 1 is a side elevation of my new weaving machine, with a portion of the driving mechanism removed in order to show the mechanism behind it;

Fig. 2 is a plan view, with the wind up mechanism removed to expose the parts below;

Fig. 3 is a transverse section, on the line 3—3 of Figs. 1 and 2, and

Fig. 4 is an end elevation, looking from the right in Figs. 1 and 2.

Referring to the accompanying drawings, 10 designates the frame of my weaving machine, and consists of the bed 11, front uprights 12, rear uprights 13, upper longitudinal braces 14, lower longitudinal braces

15, transverse brace 16 and intermediate vertical braces 17 and 18.

My improved weaving machine may conveniently be considered as consisting of the following parts: 1. Thread and fabric supporting mechanism; 2. Shuttle mechanism; 3. Reed mechanism; and 4. Power train, hence I will therefore describe it by discussing each of these parts, and then 5. The operation of the machine as a whole. 60

1. Thread and fabric supporting mechanism

Supported in any suitable and usual manner, but in proximity to the frame 10, is a spool rack 20, containing the desired number of spools 21 so that there will be one spool for each of the warp threads 22, these spools being mounted for rotation to facilitate unwinding. Each thread 22 passes through an eye 23, and through a hole in a guide plate 24, the threads being divided into two equal groups, those in one group passing through the top of the guide plate and those in the other group passing through the bottom thereof. The groups of threads are then passed over and under a pair of tension rolls 25, and then through a harness 26, 27, which facilitates the reciprocation of the two groups of threads to cause them to cross the woof, as hereinafter explained. 70

The harness members 26 and 27 each consist of a series of vertical slats 28, perforated at 29 and held in a framework 30, the latter being provided with rollers 31 adapted to bear against slotted tracks 32 85 in the front uprights 12 and to be reciprocated up and down by pistons 33, 34 which cooperate with cylinders 35, 36, as explained later on. The threads of one group go to the harness member 26, and those of the other group to the harness member 27, the division into groups being such that the alternate threads go to different harnesses. 90

From the harness 26, 27 the warp threads extend almost to the fabric support guides 37, 38, carried in bearing plates 40, mounted on the longitudinal braces 14. A piece of previously woven fabric 39 is placed between the guides 37, 38 to act as a bait, and the ends of the warp threads 22 are tied to the corre- 100

sponding threads in this fabric. As the latter is woven it is caused to pass over a roll 41, under a roll 42, back over the roll 42 and under and around a wind-up roll 43. Rolls 41 and 42 are rotatably mounted in bearings in brackets 44, 45 carried by the longitudinal braces 14, and each of the brackets terminate in upwardly extending parallel guide fingers 46 which form vertically slotted bearings for the ends of the wind-up roll 43.

through the air from one carrier to the other at the center of the machine. The reciprocating movements of the carriers are so timed that both are opened simultaneously to effect the transfer operation and then 70 immediately closed, to retain the shuttle in the second carrier, by the reversal of movement of the carriers and the consequent release of the springs 62.

Reciprocatory movements are imparted to 75 the shuttle carriers 56, 57 by the following linkage. Supported on a hub-base 73, carried by the longitudinal braces 15, are a pair of brackets 74, one on each side of the machine, and the lower end of a link 75 is 80 pivoted in each bracket at 76, while the upper end of each link is provided with a slot 77, through which extends a pin 78 secured to the outer end of each connecting rod 66.

Mounted in suitable bearings in brackets 80, 85 carried by transverse braces 79, is a rock shaft 81, which carries a lever 82. Connecting rods 83, are secured to the lever on opposite sides of, and at equal distances from the rock shaft, and the other end of 90 each connecting rod is attached to one of the links 75 just above its pivot 76. The lower arm of lever 82 is slotted at 84 to receive a pin 85 carried by a piston rod 86,

one end of which carries a piston 87 for 95 cooperation with a cylinder 88, to be described later, and the other end of which passes through a bearing in a bracket 90 carried by the sub-base 73. Consequently, when the piston rod 86 is reciprocated motion will be transmitted to the lever 82 by the pin 85, thence to the links 75 by the connecting rods 83, and then to the shuttle carriers 56, 57 by the connecting rods 66, thus moving the shuttle carriers 56, 57 from 105 the sides to the center of the machine, opening the jaws 58, transferring the shuttle from one carrier 56 to the other carrier 57, closing the jaws 58, and moving both carriers to the sides of the machine to complete 110 the laying of one woof thread. The operation is then repeated, transferring the shuttle from carrier 57 to carrier 56, and so on.

115

The shuttle is carried by oppositely-arranged shuttle carriers 56, 57, each of which consists of open-sided upper and lower jaws 58 and 60, respectively, pivoted together at 35 61, and normally held substantially closed by a spring 62 whose opposite ends bear against the rear end 63 of jaw 60 and a projecting lug 64 on the rear end of jaw 58, suitable retaining pins 65 being provided 40 in the parts 63 and 64 to hold the springs 62 in position. The front end of each of the jaws 58 and 60 is concave to conform to the shape of the shuttle 50.

The lower jaw 60 of each shuttle carrier 45 is securely attached, as by screw threads or welding, to a connecting rod 66 whose outer end is received in a bearing bracket 67, one of which is mounted on each longitudinal brace 14. The top of each upper jaw 58 is 50 provided with a slotted bracket 68 in which is secured one end of an operating rod 69 whose outer end is adapted to extend through a stop plate 70, one of which is secured to each of the front uprights 12 and longitudinal braces 14. A collar 71 is adjustably secured to the outer end of each operating rod 69 by a set screw 72 in such a position that on each instroke of the shuttle carriers 56, 57 the collars will strike the corresponding stop plates 70 just before the lower jaws 60 of the shuttle carriers come 60 into contact, thus compressing the springs 62, opening the jaws 58 and 60, and allowing the impetus caused by the movement of the shuttle carriers to throw the shuttle

When the shuttle carriers have moved from the position shown in full lines in Fig. 2 to the position shown in dotted lines therein, the woof thread 49 which extends from the fabric 39 to the shuttle 50 will occupy the position indicated by the dotted line X. To move the woof from this position to that shown by the dotted line Y, I utilize a reed 100, which consists of a cross bar 101, provided with a series of teeth 102 to provide a notch 103 for each of the warp threads 22. The reed is pivoted on a rock shaft 104, carried by brackets 105 on the transverse brace 109, and is reciprocated 130

3. Reed mechanism

by a piston 106 which cooperates with a cylinder 107 supported by the intermediate transverse brace 16. Movements of the piston 106 are transmitted to the reed 100 by 5 a piston rod 108 and a link 110 pivoted thereto, the opposite end of link 110 being pivoted in a bracket 111 carried by the cross bar 101 on the reed. When thus actuated the reed is reciprocated toward and from 10 the finished fabric 39 which is passing through the guides 37, 38. On the forward stroke the teeth 102 on the reed rise behind the last woof thread 49 and pass between adjacent warp threads 22, moving thread 15 49 forward and beating it up into proximity with the previous woof thread.

To hold the woof thread 49 tight during this beating-up step, I provide a finger 112 on each side of the machine just above the 20 longitudinal braces 14 and just in front of the position occupied by the conical end 54 of the shuttle when it is at the side of the machine. The finger 112 is operated by the movement of the cross bar 101 of reed 100 25 by the following linkage, which is duplicated on each side of the machine. An offset link 113 is pinned to the side of the cross bar 101 at 114, just above its pivotal connection with the rock shaft 104, and to the offset link 30 is pivoted one end of an extensible connecting rod 115, the other end of which is connected to one end of a bent lever 116 pivoted at 117 on the intermediate brace 17. The opposite end of lever 116 is connected 35 to a link 118, which in turn is connected to the lower end of a guide rod 120 which depends from the finger 112. Guide rod 120 and another guide rod 121, which is parallel thereto, pass through a guide plate 40 122 carried by the longitudinal brace 14. Consequently, when the reed 100 is moved forwardly, to beat up the woof, connecting rod 115 is given a simultaneous forward movement, rocking lever 116 on its pivot 45 117 and pulling downwardly on link 118 and guide rod 120, thus lowering the finger 112 so that it tightly grasps the woof thread 49 adjacent to the perforation 55 in the end of shuttle 50, holding it taut and 50 preventing the unwinding of too much thread from the bobbin in the shuttle on account of the pressure exerted on the woof 49 by the reed 100 in the beating-up operation. As soon as the piston 106 is moved in 55 the opposite direction, the reverse movement of the linkage raises the finger 112 and releases the woof thread 49.

Also pivoted to cross bar 101 by pivot 60 114 is one end of a link 130 whose other end is pivoted to the lower end of a second link 131 at 132. The upper end of link 131 is pivoted on a rock shaft 133 mounted in wind-up bracket 45. The upper end 135 of link 131 is bent forward and a pawl 134 is 65 pivotally connected to it at 136. The outer

end of the pawl rests by gravity on a ratchet 137, mounted on the end of the shaft 138 which carries roll 42. Consequently, when piston 106 swings the reed 100 forwardly, for the beating-up operation, the link 130 70 rocks the link 131 on the shaft 133, and causes the pawl 134, which is in engagement with a tooth of ratchet 137, to give the latter a counter-clockwise rotation, as viewed in Fig. 1, and advance the finished fabric 39 75 one step through the guide rolls 37 and 38, as well as winding up a previous portion of the fabric 39 on the wind-up roll 43, which is guided by the slotted bearings 46 and rests by gravity on the roll 42, being rotated 80 by friction when the roll 42 is rotated. On the reverse movement of the reed 100 the pawl 134 slides freely over the teeth of ratchet 137 and drops by gravity behind the 85 next tooth.

4. Power train

Power from any suitable source, such as a motor (not shown) is conveyed to a pulley 150 (Figs 2 and 4) on a main drive shaft 151, mounted in bearing brackets 152 carried by the bed 11. Shaft 151 is provided with a gear 153 which cooperates with a gear 154 mounted on a jack shaft 155 that is supported in bearing brackets 156 on bed 11. Consequently the rotation of shaft 151 is 90 imparted to jack shaft 155, and the power thus transmitted to shaft 151 actuates valve-tripping mechanism for the entire operation of the machine, as will now be explained.

Pistons 33, 34, 87 and 106, which have 100 been referred to previously, may be operated by any desired motive power, but I prefer to use compressed air at about 70 to 90 lbs. pressure, the supply of this air pressure to the cylinders being controlled by a series 105 of slide valves that are operated mechanically by the power transmitted to the main drive shaft 151.

There are three of these slide valves and they all operate alike. Each consists of a 110 cylinder, provided with the usual inlet and exhaust ports for the actuating fluid, a piston, and a piston rod, the latter being provided with a valve-tripping pin, which is moved first in one direction to supply air 115 to one side of the slide valve piston, and then in the opposite direction to supply air to the opposite side of the slide valve piston. The tripping of the pin is effected by a pair of cams on the main drive shaft or jack shaft, which alternately move the pin in opposite directions.

Piston 87, which controls the shuttle movement, is actuated by a slide valve 160 which is supported by a U-shaped bracket 161 on the bed 11 and consists of a cylinder 162, piston 163 and piston rod 164, the latter having a valve-tripping pin 165. The opposite end of piston rod 164 is received in a bearing bracket 166 on bed 11. Mounted 130

on the main drive shaft 151 are a pair of reversely-arranged cams 167 and 168, provided with hubs 170 and 171, and reversely-arranged pin-engaging lobes 172 and 173, respectively. The hubs 170 and 171 are provided with set screws 174, for securing them tightly to shaft 151 after they have been adjusted so as to time the contact of the lobes 172 and 173 with the pin 165 to give the desired movements to the slide valve 160 and consequently to the piston 87 and shuttle carriers 56 and 57.

Operating air for the various valves and cylinders is conveyed by piping 175 from any suitable source of supply, that for the slide valve 160 being introduced through an opening 176 in the cylinder 162. The air pressure to effect the inward movement of the shuttle carriers is conveyed from the slide valve 160 to cylinder 88 by a pipe 177, and that for the outward movement of the shuttle carriers is conveyed by a pipe 178.

A similar slide valve 180 actuates the piston 106 in cylinder 107 which operates the reed 100, finger 112 and pawl 134, but the same cams 167 and 168 on shaft 151 are used to trip a pin 181, which controls slide valve 180, as to trip the pin 165 which controls slide valve 160. Slide valve 180 is supported by a U-shaped bracket 182 on the bed 11 and consists of a cylinder 183, piston 184 and piston rod 185, the opposite end of which is received in a bearing bracket 186, also on bed 11. Piston rod 185 carries valve-tripping pin 181. Operating air is introduced into the cylinder through an opening 187 in the cylinder wall, and air pressure to effect the beating-up action of the reed is conveyed from the slide valve 180 to cylinder 107 by a pipe 190, while that for the return movement of the reed is conveyed by a pipe 188. Since the same cams 167 and 168 control both the shuttle and reed operations, these will always occur after the same time interval has elapsed.

Pistons 33 and 34, which control the up and down movements of the harness 26 and 27, respectively, are actuated by a slide valve 200, which is supported by a U-shaped bracket 201 on the bed 11, and consists of cylinder 202, piston 203, and piston rod 204, whose opposite end is received in a bearing bracket 205, also on bed 11. Piston rod 204 is provided with a valve-tripping pin 206, and the latter is actuated by reversely-arranged cams 207 and 208 carried by jack shaft 155. Cams 207 and 208 are provided with hubs 210 and 211, and reversely-arranged pin-engaging lobes 212 and 213, respectively, the hubs having set screws 214 for securing them to the jack shaft after they have been adjusted to time the contact of the lobes 212 and 213 with the pin 106 to give the desired movements to the slide valve 200, and consequently to the pistons

33 and 34, and harness 26 and 27, respectively.

Operating air is introduced into the cylinder 202 through an opening 215 in the cylinder wall, and air pressure to effect the lifting of harness 26 and the lowering of harness 27 is conveyed from the slide valve 200 to cylinders 35 and 36 by a pipe 216, while that for the lowering of harness 26 and the lifting of harness 27 is conveyed by a pipe 217.

5. Operation

Inasmuch as the operation of each part has been explained in connection with the description of that particular portion of the machine to which it relates, it is believed that the operation of my new weaving machine as a whole will be clear from the following explanation.

A piece of previously spun fabric 39 is started around the wind-up roll 43, back around rolls 42 and 41, and fed back between guide rolls 37 and 38, leaving the end exposed. The warp threads 22 are then fed from the spools 21 on spool rack 20 through the guide plate 24, around tension rolls 25, and through the harness 26 and 27, the free ends being extended to the guide rolls 37 and 38, whereupon the ends of the warp threads are then attached to the previously spun fabric 39, as by sewing them thereto. Shuttle 50 is then loaded with a bobbin, the free end of the woof 49 being threaded through the perforation 55, and tied or sewed to one edge of the previously spun fabric 39.

Power is now applied to pulley 150, and compressed air is supplied to piping 175. Pulley 150 drives shafts 151 and 155, and cams 167, 168, 207 and 208, and the latter impart reciprocating movements to the valve-tripping pins 165, 181, and 206, and hence to the slide valves 160, 180 and 200, which control the admission of the compressed air from piping 175 to the shuttle cylinder 88, reed cylinder 107, and harness cylinders 35 and 36.

This results in movements of the shuttle 50, reed 100 and harness 26 and 27 as follows: Assuming that the shuttle-carriers 56 and 57 are in the positions shown in dotted lines in Fig 2, and that the woof 49 extends, as shown in dotted line Z from the front edge of the fabric 39 to the shuttle 50, the lobe 173 on cam 168 will engage pin 165 on connecting rod 164 of slide valve 160 and move it to the position shown in Fig. 2, thus actuating piston 87 in shuttle cylinder 88 and moving the shuttle carriers 56 and 57 to the position shown in Fig. 3. As indicated in this figure, the lower jaws 60 of the shuttle carriers are thus brought almost but not quite into contact, and the sudden stoppage of the shuttle carriers, when piston 87 reaches the end of its stroke, pro-

duces a jolt which transfers the shuttle from carrier 56 to carrier 57. Stops 71 on operating rods 69 are so set that they will contact with stop plates 70 and compress springs 62, to open shuttle carrier jaws 58, the instant before the carriers are stopped, so that the shuttle can be transferred by the sudden jolt referred to. The cam 167 is so adjusted on the shaft 151 that lobe 172 will engage pin 165 and cause a reverse movement of slide valve 160, piston 87 and the shuttle carriers 56 and 57 the instant after the transfer occurs, thus releasing the springs 62 and closing the shuttle carrier jaws 58 to retain the shuttle in carrier 57 and move the carriers to the sides of the machine, as indicated by the dotted lines in Fig. 2. At this time the position of the woof 49 which has just been laid is indicated by the dotted line X. Immediately after the shuttle carriers reach the sides of the machine, the lobe 173 on cam 168 actuates the pin 181 on connecting rod 185 of slide valve 180 and moves it to the rear (Fig. 2), thus actuating piston 106 in reed cylinder 107, and rocking the reed 100 on shaft 104. This lowers finger 112 into contact with guide plate 122 and holds the woof thread 49, shown by the dotted line X of Fig. 2, taut during the continued movement of the reed, whose teeth pass between adjacent warp threads 22 and beat up the woof thread 49 until it reaches the fabric 39, and the reed reaches the dotted line position shown in Fig. 2. As explained above, this movement of the reed 100, through the linkage 130, 131, and 134, winds up the finished fabric 39 on wind-up roll 43. At this time the free end of the woof thread is in the position shown by dotted line Z' of Fig. 2, and extends from the rear edge of the fabric 39 to the shuttle 50.

Immediately after the beating-up operation, the harness 26, 27 has to be shifted to cross the warp threads 22 around the woof thread 49 which has just been beaten up. For this purpose, lobe 213 of cam 208 engages pin 206 on connecting rod 204 of slide valve 200 and moves it to the rear (Fig. 2), thus allowing compressed air to enter pipe 217, and actuate pistons 33 and 34 in harness cylinders 35 and 36, respectively, to lift harness 27 and lower harness 26.

To return the reed 100 to its inoperative position, lobe 172 on cam 167 actuates the pin 181 on connecting rod 185 of slide valve 180 and moves it to the front (Fig. 2), thus actuating piston 106 and rocking the reed 100 on shaft 104. This raises finger 112 and releases the woof thread 49, and also causes pawl 134 to drop behind the next tooth of ratchet 137.

This completes one cycle of operation and the further rotation of shaft 151 causes lobe

173 on cam 168 to again engage pin 165, on connecting rod 164, thus actuating piston 87 and moving the shuttle carriers 56, 57 to the position shown in Fig. 3 and transferring the shuttle from carrier 57 to carrier 56.

Immediately thereafter lobe 172 on cam 167 engages pin 165 and reverses the movement of slide valve 160, piston 87 and the shuttle carriers, thus moving the latter to the sides of the machine, as indicated by the dotted lines in Fig. 2. The position of the woof 49 which has just been laid is indicated by the dotted line X'.

When the shuttle carriers reach the sides of the machine, lobe 173 on cam 168 again actuates the pin 181 on connecting rod 185 and moves it to the rear (Fig. 2), thus actuating piston 106 and rocking the reed 100 on shaft 104. This lowers finger 112 into contact with guide plate 122 and holds the woof thread 49 taut during the continued movement of the reed, which beats up the woof until it reaches the fabric 39. The free end of the woof thread is then in the position indicated by the dotted line Z of Fig. 2, and extends from the front edge of the fabric 39 to the shuttle 50.

The harness 26, 27 is then shifted again, lobe 212 of cam 207 engaging pin 206 on connecting rod 204 and moving it to the front (Fig. 2), thus allowing compressed air to enter pipe 216, and actuate pistons 33 and 34 in harness cylinders 35 and 36, respectively, to lower harness 27 and lift harness 26. The reed 100 is returned to its inoperative position, finger 112 releases the woof thread 49, and pawl 134 drops behind the next tooth of ratchet 137 when lobe 172 of cam 167 again moves pin 181 to the front (Fig. 2) to actuate piston 106.

This completes a second cycle of operation and these two cycles are repeated alternately during the entire period of operation of my weaving machine.

Throughout my specification I have frequently used the terms "thread" and "fabric" and, in order that no undue limitation on the scope of my invention may be inferred from the use of these terms, I desire to have it understood that they are used in the broadest possible sense so that the term "thread" will include single strands or groups of strands of flexible or semi-flexible material of any kind suitable for weaving, such as cotton, wool, silk, rubberized cord, and wire, and so that the term "fabric" will include the product which results from weaving single strands or groups of strands of the materials referred to, or any similar materials.

From the above description it will be apparent that I have invented a new and useful weaving machine which is capable of handling a wide range of materials, and

that my invention is susceptible of various modifications within the scope of the following claims.

I claim:

5. 1. A shuttle carrier provided with upper and lower jaws, which are pivoted together, resilient means for normally maintaining the jaws closed, and means independent of the shuttle for overcoming said resilient means 10 to simultaneously open the jaws when the carriers are at the inner limit of their stroke.
2. A shuttle transfer mechanism which consists of a pair of shuttle carriers provided with spring-controlled jaws, means for reciprocating the shuttle carriers toward and from each other, and means for throwing the shuttle from one carrier to the other.
3. A shuttle transfer mechanism which consists of a pair of shuttle carriers provided 20 with spring-controlled jaws, means for reciprocating the shuttle carriers toward and from each other, and means for transferring the shuttle from one carrier to the other, said means consisting of actuating means for the 25 carriers which stop them suddenly before contacting and thus produce a jolt to effect the transfer.
4. A shuttle transfer mechanism which consists of a pair of shuttle carriers provided 30 with pivoted jaws, means for reciprocating the shuttle carriers toward and from each other, and means for opening and closing the jaws of both shuttle carriers at the same time, the jaws being opened when the 35 carriers are at the inner limit of their stroke.
5. A shuttle transfer mechanism which consists of a pair of shuttle carriers provided with pivoted jaws, means for reciprocating the shuttle carriers toward and from 40 each other, and means for opening and closing the jaws at the desired time, said means including adjustable stops attached to the jaws, and means for limiting the travel of these stops, as the carriers approach one 45 another, in order to simultaneously open the jaws when the carriers are at the inner limit of their stroke.
6. A shuttle transfer mechanism comprising a pair of shuttle carriers, each of which 50 carriers consists of a pair of pivoted jaws, means for reciprocating said carriers toward and from one another in a horizontal plane, means for abruptly stopping the travel of the carriers at a predetermined point in their 55 travel, means for opening the jaws just prior to said abrupt stoppage in order to transfer the shuttle from one carrier to the other by the jolt of said abrupt stoppage, and means for retaining the shuttle in the carrier to 60 which it is transferred.
7. A shuttle transfer mechanism comprising a pair of shuttle carriers, each of which carriers consists of a pair of pivoted jaws, means for reciprocating said carriers toward 65 and from one another in a horizontal plane,
- means for abruptly stopping the travel of the carriers at a predetermined point in their travel, adjustable means for opening the jaws just prior to said abrupt stoppage in order to throw the shuttle from one carrier to the other, and means for retaining the shuttle in the carrier to which it is transferred.
8. In a shuttle transfer mechanism, the combination of a shuttle, a pair of shuttle carriers consisting of spring-operated hinged jaws, means for moving both carriers toward one another and suddenly stopping them before they come into contact, to throw the shuttle from one carrier to the other, and means for facilitating the proper positioning of the shuttle in the shuttle carrier which is to receive it and for preventing its moving longitudinally with respect to the shuttle carrier.
9. In a shuttle transfer mechanism, the combination of a shuttle, a pair of shuttle carriers consisting of spring-operated hinged jaws, means for moving both carriers toward one another and suddenly stopping them before they come into contact, to transfer the shuttle from one carrier to the other, and means for facilitating the proper positioning of the shuttle in the shuttle carrier which is to receive it and for preventing its moving longitudinally with respect to the shuttle carrier, said means consisting of outwardly-flared flanges provided on the shuttle at a distance apart which is equal to the length of the jaws of the shuttle carriers.
10. The combination of a shuttle and a pair of shuttle carriers, the former being provided with flanges for facilitating its proper positioning in the shuttle carriers, said flanges being spaced apart a distance equal to the length of the shuttle carriers, and the latter consisting of pivoted jaws which are normally spring held in closed position, but which are opened at predetermined times to permit the transfer of the shuttle from one carrier to the other.
11. A weaving machine which comprises a thread supporting mechanism, a shuttle mechanism, a reed mechanism, and a power train for operating these parts, the shuttle mechanism having shuttle carriers and means for throwing the shuttle through the air from one shuttle carrier to the other, and the shuttle carriers having portions which support the shuttle while it is being thrown, and the power train consisting of separate fluid-actuated pistons for operating the shuttle mechanism, reed mechanism and thread supporting mechanism, a drive shaft, and a series of cam-controlled slide valves actuated by the drive shaft for controlling the supply of fluid to the pistons.
